[57] ABSTRACT

A sectionalized ladder of which the sections are provided with matching proximate, hinged together end portions to produce an integrated assembly; such hinged relationship permitting both sections to be brought into alignment with each other to produce an aligned section ladder of length greater than either of the sections, or may be folded into facial contact with each other to produce a double thickness unit of the length of a section, and locked in such aligned section thickness or such double thickness condition for ready transport or storage.

4 Claims, 3 Drawing Figures

PATENTED DEC 18 1973

3,779,343

FIG. 1

FIG. 2

FIG. 3

**UNITS FOR CONNECTING TOGETHER
SUCCESSION LADDER SECTIONS**

This application is a continuation in part of my earlier filed application, Ser. No. 249,152, filed May 1, 1972, titled Ladder Construction.

In the drawing:

FIG. 1 shows a perspective view of a portion of a ladder embodying features of my present invention, such view showing two ladder sections hinged together in full line showing, and also shows by dashed lines the position into which the lower section may be turned into parallelism with the adjacent section, and also shows by dashed lines a locking plate which may serve to lock the two sections in alignment with each other;

FIG. 2 shows in perspective and on enlarged scale as compared to FIG. 1, a view looking at the top surface of the structure and shows how the proximate portions of the two ladder sections may be secured together by a transition plate hinged to the top surface of one section, and locked to the top surface of the other section by a convenient locking element; and

FIG. 3 shows in perspective and disassembly, the elements shown in FIG. 2.

Looking first at FIG. 1, the two ladder units are shown at 10 and 11, their proximate lower end surfaces being hinged together by the hinge 12 which hinge comprises a unit including the socket assemblies or sections 13 and 14. Each of such sections 13 and 14 includes gripping elements of the form shown in FIG. 3. Each of such gripping elements is of generally U-shape, provided with outwardly extending flanges, (on the unit 13, and on unit 14), provided with openings through which tie bolts may be extended to draw the units together in gripping fashion thus firmly gripping the side bars of the ladder units. Such flanges are shown at 15 on the units 13 and at 16 on the units 14. The units 13 and 14 of proximate ladder elements are provided with companion end hook shaped extensions 16 and 16^a which interconnect when the proximate ends of ladder sections are brought together, through which proximate extensions there may be extended pins or bolts 17 such as shown in FIG. 3, thus hinged connecting together the proximate ends of successive units 13 and 14. In FIG. 1 two proximate end portions have been connected together at 12, so that the two units 13 and 14 may be turned into non-alignment or may be aligned as shown in FIG. 2.

When proximate sections have been aligned (as shown in FIGS. 1 and 2), they may be secured in such alignment, as follows:

A locking plate 18 may be set against the surfaces of the two sections which sections have been aligned, such plate being connected to the two sections in convenient manner, as by hinging such plate 18 to one of the sections, as shown at 19, the other end portion of such hinge plate being connected to the proximate section by provision of an opening in such plate 18 at position to receive the loop 20 carried by the companion section, through which loop may be extended a locking unit 21 as shown in FIG. 2.

As shown in the drawings, locking unit 21 is connected to one of the engaging sets of flanges 15 and 16 by a tie chain 22 secured to one end 23 thereof, which tie chain 22 carries a snap fastener 24 that is applied to the other end 25 of unit 21 to retain same applied to the loop 20. As best shown in FIG. 2, unit 21 comprises a plate element that is generally tapered between its ends

23 and 25, with its end 25 being proportioned to be freely received through loop 20; unit 21 is angled to dispose its end 25 to one side of the assemblies 13 and 14 for ready application thereto of snap fastener 24.

I claim:

1. In a sectionalized ladder arrangement including two ladder sections each comprising a pair of spaced parallel side bars having step elements extending therebetween, a hinge device for hinging together the side bars on the respective sides of the ladder sections, at adjacent ends, said hinge device comprising:

a pair of socket assemblies each comprising: first and second half sections of U-shaped transverse cross-sectional configuration each defining laterally extending securing flanges,

said sections of each assembly being proportioned to be applied on either side of a ladder section side bar end and receive same,

said flanges of the respective assembly half sections being disposed in opposed relation when such half sections receive a ladder section side bar end, fastener means for securing together the opposed half section flanges of the respective assemblies to draw the respective half sections against the ladder section side bar end engaged by same to make such sections fast to such side bar end, with the second sections of said assemblies being hinged together for relative movement into and out of longitudinal alignment,

a locking plate hinged to the first section of one of said assemblies and mounted for movement into flush engagement with the first section of the other assembly when said assemblies are in longitudinal alignment,

said locking plate being apertured to pass through same a loop carried by said other assembly first section when said locking plate is in said flush engagement with said other assembly first section, and a keeper element secured to said other assembly and proportioned for close fitting engagement with said loop when said loop is passed through said locking plate,

said keeper element being secured to said other assembly by a tie member extending between one end of said keeper element and said other assembly,

said tie member carrying a snap fastener and said keeper element having the other end of same apertured to receive said snap fastener to maintain said keeper element within said loop when said keeper element has been applied to said loop to lock said assemblies in aligned relation.

2. The hinge device set forth in claim 1 wherein: said tie member is made fast to one of said flanges of said other assembly.

3. The hinge device set forth in claim 1 wherein: said keeper element is tapered longitudinally thereof from said other end of same to said one end of same with said other end of same being proportioned to freely pass through said loop and said one end of same being proportioned for said close fitting engagement with said loop.

4. The hinge device set forth in claim 3 wherein: said keeper element is angled to dispose said other end of same to one side of said assemblies for ready application thereto of said snap fastener.
